UNITED STATES PATENT OFFICE.

JONATHAN McC. LOPER, OF PITTSBURG, PA., ASSIGNOR OF ONE-HALF OF HIS RIGHT TO DANIEL F. CALMUS, OF SAME PLACE

IMPROVEMENT IN TUBE-THREAD PROTECTORS.

Specification forming part of Letters Patent No. 222,920, dated December 23, 1879; application filed October 18, 1879.

To all whom it may concern:

Be it known that I, JONATHAN McC. LOPER, of Pittsburgh, in the county of Allegheny and State of Pennsylvania, have invented certain new and useful Improvements in Tube-Thread Protectors; and I do hereby declare the following to be a full, clear, and exact description of the invention, such as will enable others skilled in the art to which it pertains to make and use it, reference being had to the accompanying drawing, which forms part of this specification.

My invention relates to an improvement in tube-thread protectors; and it consists in a ring made of suitable elastic material, inclosed in a metallic shell, by which it is protected, the said ring to be screwed upon the thread on the tube, covering the same and preventing injury during transportation, as will be more fully described hereinafter.

The accompanying drawing represents a longitudinal section of my invention.

A represents a metallic pipe having a screw-thread formed on the outside of its end. If this thread is left unprotected during transportation it is almost sure to be so battered and injured as to necessitate recutting before the screw is fit for use. In order to form a protector for this thread a cylinder, B, is made from paper or some soft tough material, which can be screwed on the end of the pipe, either the full length of the thread, or just far enough up to protect that part of the thread which is to be brought into actual use.

Where the pipe is small, or the screw very short, the cylinder B alone may be used; but

where the pipe is large the cylinder is inclosed in a sheet-metal cover, C. This cover gives additional strength to the cylinder, and protects it from being cut or injured. This cover may be turned down at its outer end over the end of the cylinder, as shown; but this is not necessary.

Heretofore wood has been used to protect the screws; but the great trouble with it is that it splits whenever the ends of the pipe are struck or are dropped, and it warps and cracks from the heat, and had to be abandoned as impracticable.

Where the cylinders are made from paper-pulp and compressed to a suitable hardness, they can be screwed upon the pipe, where they stick so tightly that they can only be removed by the application of considerable force, and then can be used again and again.

Having thus described my invention, I claim—

1. A screw-thread protector, to be applied to the outside of the end of a pipe, that is made of paper or similar material, substantially as shown.

2. A tube-protector consisting of a cylinder, B, made of a soft tough material and inclosed in a metallic cover, C, substantially as described.

In testimony that I claim the foregoing I hereunto set my hand this 12th day of October, 1879.

JONATHAN McC. LOPER.
